UNITED STATES PATENT OFFICE.

MORTON E. CONVERSE, OF WINCHENDON, MASSACHUSETTS.

BED.

SPECIFICATION forming part of Letters Patent No. 556,334, dated March 17, 1896.

Application filed March 23, 1894. Serial No. 504,881. (No model.)

To all whom it may concern:

Be it known that I, MORTON E. CONVERSE, a citizen of the United States, residing in the town of Winchendon, Massachusetts, have invented 5 a certain new and useful Improvement in Beds, of which the following is a specification.

My invention relates to folding beds, and the object is to provide a bed that may be 10 folded up and packed away in small compass.

My invention consists in the construction and novel arrangement of parts as hereinafter specified, and particularly pointed out in the claim.

15 In the drawings similar letters of reference designate corresponding parts in all figures.

Figure 1 represents a side elevation of a bedstead embodying my invention. Fig. 2 is an edge view thereof when folded. Fig. 3 is an 20 end elevation.

The bottom frame of the bed comprises the side bars, D, and the end bars, D', secured together in any desired manner. The end bars, D', or extension d thereon are provided with 25 trunnions d', adapted to engage in sockets d², formed in portions of the head and foot boards D". It will be seen by this construction that the head and foot boards may be folded closely upon the bottom frame, as indicated in Fig. 2.

30 It will be seen that the head and foot boards are extended downward to form legs for the bed, and therefore when the bed is folded the head and foot boards, with the legs, will be on the upper side of the bottom frame, thus allowing 35 the bed to be folded in a small space, which would not be the case were the legs separate from the head and foot boards.

The ends of the side boards form abutments for the head and foot boards when the same are in a vertical position, and these head and 40 foot boards may be locked in this vertical position relatively to the side bars by means of the removable side boards, D², the ends of which bear against the inner surface of the head and foot boards.

45 To hold the side boards in position, I provide their lower edges with pins d³ adapted to engage in sockets d⁴ in the side bars, D. These side bars hold the bedstead in a rigid open position, and when it is desired to fold 50 the bedstead of course the side bars must be removed.

What I claim as new, and desire to secure by Letters Patent, is—

A folding bed comprising a bottom frame 55 having side and end bars rigidly secured together, a head-board having sockets formed in the inner side of its posts, an extension-piece on the head end of the bottom frame having trunnions to enter the sockets, a foot-board having sockets in its posts, an extension-piece on the foot end of the bottom frame, an extension-piece on said foot end having trunnions to engage in the sockets of the foot-board, and side boards having pins to enter 60 holes in the side bars of the bottom frame, the 65 said side being wholly removable, and, when in position, adapted to support the head and foot boards vertically, substantially as specified.

MORTON E. CONVERSE.
